RAILWAY LIGHT SIGNAL

Bernard E. O'Hagan, Swissvale, Pa., assignor to
The Union Switch & Signal Company, Swiss-
vale, Pa., a corporation of Pennsylvania

Application March 18, 1932. Serial No. 599,633

8 Claims. (Cl. 246—219)

My invention relates to apparatus for the control of railway light signals, and has for an object the provision of novel and improved means for automatically causing a light signal to give 5 a more restrictive indication when traffic conditions warrant a less restrictive indication and the lamp or lamps which should give such less restrictive indication fail.

I will describe two forms of apparatus embodying my invention, and will then point out the novel features thereof in claims.

In the accompanying drawing, Fig. 1 is a diagrammatic view showing one form of apparatus embodying my invention. Fig. 2 is a view similar to Fig. 1, but showing a modification of certain parts of the apparatus and also embodying my invention.

Similar reference characters refer to similar parts in each of the views.

20 Referring first to Fig. 1, the reference characters H and D designate the usual home and distant relays respectively of a railway signaling system, and the reference character S designates a light signal controlled by these relays. This signal comprises three lamps G, Y, and R, which lamps, when lighted, indicate proceed, caution, and stop, respectively. In accordance with usual practice, the beam projected from lamp G may be green, the beam projected from lamp Y may 25 be yellow, and the beam projected from lamp R may be red. The indication given by lamp G is less restrictive than that given by either lamp Y or R, and the indication given by lamp Y is less restrictive than that given by lamp R.

30 Lamp G is provided with a circuit which passes from terminal B, through front contact 1—7 of relay H, front contact 2—3 of relay D, and the lamp G to terminal O of the same source of current. Lamp Y is provided with a circuit which 35 includes front contact 1—7 of relay H and back contact 2—4 of relay D. Lamp R is provided with a circuit which includes back contact 1—8 of relay H. It follows that when both relays H and D are energized, lamp G will be lighted; 40 when relay H is energized and relay D deenergized, lamp Y will be lighted; and when relay H is deenergized, lamp R will be lighted. The structure and operation of the apparatus thus far described are in accordance with usual and standard practice, and will be understood without further detailed explanation.

The reference character C designates a thermosensitive device which is exposed to heat from the lamp G, a lens L preferably being interposed 45 between the lamp and the device to concentrate

heat rays on a thermosensitive member 9 of this device. The device C comprises a contact 9—10, which is normally closed but which opens in response to the heat rays from lamp G when this lamp is lighted. The device C also comprises two 50 heating windings 11 and 12, either one of which, when energized, will serve to open contact 9—10.

Lamp Y is provided with an auxiliary circuit which passes from terminal B, through front contact 1—7 of relay H, front contact 2—3 of relay 65 D, contact 9—10 of device C, and the lamp Y to terminal O. It follows that when both relays H and D are energized, and the contact 9—10 of device C is closed, lamp Y will be lighted.

The heating winding 11 of device C is provided with a circuit which passes from terminal B, through front contact 1—7 of relay H, back contact 5—6 of relay D, and the winding 11 to terminal O. It follows that when the caution lamp Y should be lighted, winding 11 will be 70 energized. Heating winding 12 is provided with a circuit which passes from terminal B, through back contact 1—8 of relay H, and winding 12 to terminal O. It follows that when the stop lamp R should be lighted, winding 12 will be 75 energized.

The operation of the apparatus shown in Fig. 1 is as follows: As illustrated in this view, lamp G is lighted because both relays H and D are energized. The thermosensitive device C is therefore receiving heat from lamp G, so that contact 9—10 is open. It follows that the auxiliary circuit for caution lamp Y is open at this contact. I will now assume that with the parts in the condition illustrated in the drawing the proceed 80 lamp G burns out. Contact 9—10 of device C will then close, so that the caution lamp Y will become lighted by virtue of its auxiliary circuit. The signal S will then give the caution indication.

The purpose of the heating windings 11 and 12 is to prevent momentary simultaneous lighting of lamps Y and G when the indication given by the signal should change from caution to proceed, or from stop to proceed. To explain this more in detail, I will assume that relay H is energized 90 and relay D deenergized, so that the caution lamp Y is lighted. Heating winding 11 will then be energized so that contact 9—10 of the thermosensitive device C will be open. If now relay D becomes energized, lamp G will become lighted 100 but lamp Y will immediately become extinguished, because its main circuit will be opened at contact 2—4 of relay D and its auxiliary circuit will be open at contact 9—10 of device C. The parts are so proportioned that the heat from lamp G 105

will become effective to keep contact 9-10 open before this contact will close due to the deenergization of winding 11. In the absence of winding 11 under the conditions just set forth, lamps 5 Y and G would be momentarily simultaneously lighted, because contact 9-10 would be closed while lamp Y is lighted, and this contact would not open until lamp G had been lighted long enough to heat the thermosensitive member 9 of 10 the device C.

Similarly, if relay H is deenergized, so that lamp R is lighted, heating element 12 of device C will also be energized. Then, if relays H and D become energized to supply current to lamp G, contact 9-10 will be open and will not close during the transition period, so that there will be no momentary lighting of lamp Y.

Referring now to Fig. 2, the apparatus shown in this view is similar to that shown in Fig. 1, 20 except that the heating windings are omitted from the thermosensitive device C and the function of these windings is accomplished by a slow-releasing relay R having two separate windings 13 and 14, either one of which when energized 25 will open the back contact 15 of this relay. The circuit for lamp G, the main circuit for lamp Y, and the circuit for lamp R are the same as in Fig. 1. The auxiliary circuit for lamp Y is from terminal B, through front contact 1-7 of relay H, front contact 2-3 of relay D, contact 9-10 30 of the thermosensitive device C, back contact 15 of relay R, and lamp Y to terminal O. Winding 13 of relay R is provided with a circuit which includes front contact 1-7 of relay H and back 35 contact 5-6 of relay D. This winding is energized, therefore, when the caution lamp Y is lighted by virtue of its main circuit. Winding 14 of relay R is provided with a circuit which includes back contact 1-8 of relay H, so that this 40 winding is connected in multiple with the stop lamp R and is energized whenever the circuit for this lamp is closed.

As illustrated in Fig. 2, lamp G is lighted because both relays H and D are energized. The 45 thermosensitive device C is therefore receiving heat from lamp G so that the auxiliary circuit for lamp Y is open at contact 9-10 of this device. I will now assume that with the parts in the conditions illustrated in Fig. 2 the lamp G burns 50 out. Contact 9-10 will then close, and since relay R is deenergized, the auxiliary circuit for lamp Y will become lighted.

When relay H is energized and relay D is deenergized, the main circuit for the caution lamp 55 Y will be closed and relay R will be energized, because current will be supplied to its winding 13. If now relay D becomes energized, lamp G will become lighted but the auxiliary circuit for lamp Y will not become closed, because this circuit 60 will be kept open at back contact 15 of relay R until after contact 9-10 of the thermosensitive device C opens. Similarly, if relay H is deenergized so that the stop lamp R is lighted, relay R will also be energized, because current will be 65 supplied to its winding 14. If now both relays H and D become energized, lamp G will become lighted, but the auxiliary circuit for lamp Y will not be closed because this circuit will be held 70 open at back contact 15 of relay R until after contact 9-10 opens.

Although I have herein shown and described only two forms of apparatus embodying my invention, it is understood that various changes and modifications may be made therein within

the scope of the appended claims without departing from the spirit and scope of my invention.

Having thus described my invention, what I claim is:

1. In combination, a home relay and a distant relay, a light signal having a proceed lamp and a caution lamp, means for lighting said proceed lamp when both of said relays are energized, means for lighting said caution lamp when said home relay is energized and said distant relay is deenergized, and means including a thermosensitive device exposed to heat from said proceed lamp for causing said caution lamp to become lighted when both of said relays are energized if the proceed lamp is burned out. 80 85 90

2. A multiple aspect light signal for railroads having lamps controlled according to traffic conditions ahead, and automatic means independent of traffic conditions and involving a thermosensitive device responsive to the heat emitted by a less restrictive lamp for lighting a more restrictive lamp if the less restrictive lamp fails and traffic conditions are such that the less restrictive lamp should be lighted. 95

3. A multiple aspect light signal for railroads having lamps controlled by traffic conditions ahead and giving yellow and green indications respectively, and automatic means independent of traffic conditions and involving a thermosensitive device exposed to heat emitted by the green lamp for lighting the yellow lamp if the green lamp fails and traffic conditions are such that the green lamp should be lighted. 100 105 110

4. In combination, a railway light signal having a lamp which when lighted gives a less restrictive indication and a second lamp which when lighted gives a more restrictive indication, a thermosensitive device exposed to heat from said first lamp and having a normally closed contact which opens when the first lamp is lighted, a circuit for said first lamp including a first controlling contact, a main circuit for said second lamp including a second controlling contact, and an auxiliary circuit for said second lamp including said first controlling contact and the contact of said thermosensitive device. 115 120 125

5. In combination, a railway light signal having a lamp which when lighted gives a less restrictive indication and a second lamp which when lighted gives a more restrictive indication, a thermosensitive device exposed to heat from said first lamp and having a normally closed contact which opens when the first lamp is lighted, a circuit for said first lamp including a first controlling contact, a main circuit for said second lamp including a second controlling contact, an auxiliary circuit for said second lamp including said first controlling contact and a contact of said thermosensitive device, and means operating when the main circuit for said second lamp is closed to supply heat to said thermosensitive device independently of said first lamp and to thereby keep the contact of said device open even though the first lamp is not lighted. 130 135 140

6. In combination, a railway light signal having a lamp which when lighted gives a less restrictive indication and a second lamp which when lighted gives a more restrictive indication, a thermosensitive device exposed to heat from said first lamp and having a normally closed contact which opens when the first lamp is lighted, a circuit for said first lamp including a first controlling contact, a main circuit for said second lamp including a second controlling contact, an auxiliary circuit for said second lamp including said first 145 150

tact and the contact of said thermosensitive device, and means for preventing momentary simultaneous lighting of said two lamps when the main circuit for the second lamp becomes open and the circuit for the first lamp becomes closed.

7. In combination, a railway light signal having proceed, caution and stop lamps, a thermosensitive device exposed to heat from the proceed lamp and having a normally closed contact which opens when the proceed lamp is lighted, a circuit for the proceed lamp, a main circuit for the caution lamp, and a circuit for the stop lamp, an auxiliary circuit for the caution lamp including the contact of said thermosensitive device, two heating windings for said thermosensitive device, means for energizing one of said heating windings when the main circuit for said caution lamp is closed, and means for energizing

the other heating winding when the circuit for the stop lamp is closed.

8. In combination, a railway light signal having proceed, caution and stop lamps, a thermosensitive device exposed to heat from the proceed lamp and having a normally closed contact which opens when the proceed lamp is lighted, a circuit for the proceed lamp, a main circuit for the caution lamp, and a circuit for the stop lamp, an auxiliary slow-releasing relay having two windings, an auxiliary circuit for the caution lamp including the contact of said thermosensitive device and a back contact of said auxiliary relay, means for energizing one winding of said auxiliary relay when the main circuit for the caution lamp is closed, and means for energizing the other winding of said auxiliary relay when the circuit for said stop lamp is closed.
